UNITED STATES PATENT OFFICE.

HOWARD E. WATKINS, OF NEW YORK, N. Y., ASSIGNOR TO OXLEY ENOS COMPANY, OF NEW YORK, N. Y., A CORPORATION OF NEW YORK.

DESIGN FOR A CHANDELIER.

SPECIFICATION forming part of Design No. 36,194, dated January 20, 1903.

Application filed November 29, 1902. Serial No. 133,291. Term of patent 7 years.

To all whom it may concern:

Be it known that I, HOWARD E. WATKINS, a citizen of the United States, and a resident of New York city, borough of Manhattan, county and State of New York, have invented and produced a new, original, and ornamental Design for a Chandelier, of which the following is a specification, reference being had to the drawing accompanying and forming part of the same, which shows a chandelier embodying this design in perspective.

As indicated in the drawing, the design comprises the fluted shaft A, having the capital B at the upper end of the same, this capital comprising a convex boss at its lower end and its upper flaring portion having a fluted outline C. The spirally-arranged beading which ornaments the upper portion of this capital terminates at the extreme outer edge of the same in the detached beads which continue each line of beading. The shaft is interrupted by the flaring ornament D, having the wavy outline indicated and being ornamented by the beading E, which, as is shown, terminates at the upper end of the same in detached beads which continue each line of beading. The lower end of the shaft is provided with the similar flaring ornament F, which rises from the annular beaded band G. Below this band the body of the chandelier flares outward, as indicated at H. The upper portion K of this body is formed with the spirally-arranged separated beading L of va-

rying pitch, as indicated, each row of beading merging into the detached beads shown. 35 The band M, extending around the body, is enriched by the row of rams' heads O, which serve as supports for the fluted curved arms P, the lower portion of the body below the band comprising the fluted cylindrical portion and 40 the conical portion N, in which the flutes gradually terminate, as indicated. Each of the arms P has the compound curved formation shown and is enriched by the spiral ornament of conventional leaf design near its inner end. 45 Each arm is also interrupted by the smooth annular portion from which depends the floral ornament Q. At the outer end of the arm is the annular fillet R, above which rises the dish-shaped ornament S, having the central smooth boss and the flaring outer portion on which are located the spirally-arranged separated beads T. Above 50 this ornament is the calyx-shaped design U, having a smooth lower portion and the similar beaded flaring upper portion and terminating in the fluted edge V. Above the edge V there is formed a flat drip-cup W and the conventional candle Y.

What is claimed as new is—

The ornamental design for a chandelier, substantially as shown and described.

HOWARD E. WATKINS. [L. S.]
